UNITED STATES PATENT OFFICE

ERICH PAUL GUIDO WUNSCH, OF STEGLITZ, NEAR BERLIN, GERMANY, ASSIGNOR TO
ASKANIA-WERKE AKTIENGESELLSCHAFT VORMALS CENTRALWERKSTATT DESSAU
UND CARL BAMBERG-FRIEDENAU, OF BERLIN-FRIEDENAU, GERMANY

COMPASS

Original application filed February 29, 1924, Serial No. 696,103, and in Germany March 14, 1923.
Divided and this application filed February 20, 1925. Serial No. 10,719.

My application for Letters Patent Serial No. 696,103, filed February 29th, 1924, of which the present application is a divisional one, relates to a process and means for the 5 frictionless transmission of movement from a moving primary element to a secondary element to be moved, which can be utilized in various branches of industry. According to the said invention a very slight movement 10 is transmitted from a primary element, for instance such as is usually automatically effected on the said element by an instrument, to a secondary controlling or setting element or to a servomotor, whereupon the 15 said secondary element or servomotor effects the required operation.

The present invention relates to a practical application of the devices claimed in the said copending application and shows how 20 the said process and means may be used in connection with a compass.

Compasses are known in which the movements of the needle are indicated at a distance and in which the movement of the compass needle is transmitted to the ship-steering or other means.

According to my invention this result is reached by new, more effective means. I use a tube through which flows a pressure medium, the outflowing medium controlling means for indicating or transmitting the movements of the compass needle to the respective devices.

The tube is controlled by a separate magnetic system which has a stationary axis and which is magnetically coupled to the needle of a compass. The arrangement is thus considerably simplified and the pressure medium is entirely prevented from having any action upon the fluid compass.

The device according to this invention is intended to indicate deviations from a set course or to control automatically the ship-steering means when such deviations occur.

A constructional example of the device according to the present invention is diagrammatically illustrated in the accompanying drawing in which Fig. 1 is a side view, partly 0 in section, showing the device in combination

with an indicating device consisting of a pressure gauge, while

Fig. 2 illustrates a servo-motor controlled by the compass, said figure being a plan-view, partly in section.

Fig. 3 is an elevation of the device shown in Fig. 2.

In the casing 5 of the compass is mounted the card 56. On the bottom of the said casing is mounted in a bracket 57, a small device of magnetic material 58 which may be made of soft iron. The magnetic moment of the said device 58 is extremely small compared to that of the main magnet system or needle 65 of the fluid compass so that the two devices are magnetically coupled together, and the magnet device 58 follows exactly every movement of the needle of the fluid compass, without the magnetism of the earth exercising any perceptible influence. To the device 58 is secured a pipe 59 bent at an angle. The downward end of the said pipe coincides with the axis of rotation of the device 58. The bottom orifice of the pipe is open and into the same opens the nozzle of a pipe 60 through which a liquid under pressure or a compressed gas, preferably compressed air, is supplied. The pipe 59 could be provided with a balance weight 61 and has an outlet nozzle 62 which is situated opposite the open end of a pipe 63. The pipe 63 leads to that point at which the deviation of the ship from a set course is to be made visible and terminates there for instance is a pressure gauge 64.

The working of the device described is as follows:—

When the compass needle 65 swings relatively to the casing 55, the device 58 will execute an exactly identical oscillation about its own axis, independently of the position of the casing and independently of the action of the magnetism of the earth and will turn the pipe 59 correspondingly. The compressed air escaping from the pipe 60 and passing through the pipe 59, passes into the pipe 63 and produces in the latter a given pressure which will be indicated by the pressure gauge 64. This pressure depends on

the relative positions of the pipe 63 and nozzle 62 and is a maximum when the vessel is on the desired course. When the needle swings to one or to the other side, the nozzle 62 will also be moved to a greater or less extent away from the centre of the mouth of the pipe 63. The pressure in the pipe 63 will therefore fall to a greater or less extent, and the pressure gauge 64 will indicate a corresponding movement. If it is desired to utilize the device for automatically executing a movement or a setting, for instance for automatic control of the steering of the vessel carrying the compass, the nozzle 62^a could be arranged, in accordance with Figure 2, opposite the mouth of two pipes *f*¹ and *g*¹ which are carried to the ends of a cylinder *h*¹. According as the needle 58^a corresponding to the device 58 of Figure 1 swings to the right or to the left, the compressed air escaping from the nozzle 62^a arranged on the pipe 59^a connected with the needle 58^a and the balance weight 61^a will pass to the one or to the other side of the cylinder, thereby producing a difference of pressure between the two sides of the piston *i*, so that the piston will be moved. The piston is connected in any desired manner to the ship-steering means and controls them in such a manner that an automatic setting of said steering means takes place when a deviation from the set course occurs.

I wish it to be understood that I have shown and described merely one example of the invention in connection with a certain system of a compass. However it will be evident to those skilled in the art that it may be used also in connection with other kinds of such plants without departing from the spirit of the invention.

Having now particularly described and ascertained the nature of my said invention and in what manner the same is to be performed, I declare that what I claim is:

45 In a compass, particularly a fluid compass in combination a main magnet system, a separate device of magnetic material having a stationary axis coinciding with the axis of the main magnetic system, said device being magnetically influenced by the main system and turned by it about its axis, a compressed-fluid tube connected with said separate device and controlled by it and having an outlet radial to the axis of the magnetic system and means to be operated in correspondence with the movement of the main magnet system and including means cooperating with the jet of fluid escaping from the outlet of said tube whereby said first mentioned means are controlled.

In testimony whereof I have affixed my signature.

GUIDO WUNSCH.
